United States Patent Office

Des. 185,068
Patented May 5, 1959

185,068

BOOK

Robert B. Clive, New York, and Bernard Waber,
Kew Garden Hills, N.Y.

Application June 30, 1958, Serial No. 51,602

Term of patent 3½ years

(Cl. D6—2)

Figure 2 is a similar perspective view thereof as it appears in open position;

We claim:

The ornamental design for a book, as shown.
